NECKTIE RETAINER

Walter L. Weinschreider, Chicago, Ill.

Application May 21, 1934, Serial No. 726,854

5 Claims. (Cl. 24—85)

My invention relates to articles generally known as tie clasps, and engageable with the shirt front to hold a four-in-hand type of necktie in place, and my main object is to provide a device of this kind which is entirely invisible from the front.

A further object of the invention is to construct the device with means for attaching the same fixedly to the back of the necktie front, whereby to be carried by the same in readiness for application to the tail of the necktie and the front of the shirt.

A still further object of the invention is to employ locking elements in the attaching means, whereby to prevent the accidental disengagement of the retainer from the necktie.

Another object of the invention is to design the novel retainer in one piece and for easy handling by any average person.

An additional object of the invention is to construct the retainer with a locking feature which has a continuous hold on the part locked.

With the above objects in view and any others that may suggest themselves from the specification and claims to follow, a better understanding of the invention may be had by reference to the accompanying drawing, in which—

Fig. 1 is a rear view of a collar and necktie assembly, showing the novel retainer in readiness for application to the necktie tail and the shirt front;

Fig. 2 is a magnified horizontal section showing the retainer applied to the parts mentioned;

Fig. 3 is a magnified elevation of the retainer from the rear side;

Fig. 3a is a section on the line 3a—3a of Fig. 3;

Fig. 4 is an elevation of a modified retainer, partly in section;

Fig. 5 is a plan view of the modified retainer;

Fig. 6 is an elevation, partly in section, of a second modification;

Fig. 7 is a plan view of such second modification;

Fig. 8 is an elevation, partly in section, of a third modification; and

Fig. 9 is a plan view of such third modification.

Necktie retainers are usually of the clamp type and for the single purpose of engaging the parts clamped in order to hold them together. Should the parts be separated, the retainer falls or remains free and apart, subjecting it to being lost or easily mislaid. In accordance with the objects outlined above, I have devised a retainer which is carried by the necktie as long as the latter is to be used, and is transferable to a different necktie

if a change is to be made. Thus, the retainer is virtually a part of the necktie and not easily lost or mislaid, and can be located readily at any time that it is wanted.

In carrying out the invention, the novel retainer is formed from a thin strip of metal, having mainly a straight section 10, a bend 10a at one end thereof, and a return section 10b from the bend.

In the preferred form illustrated in Figs. 1 to 3, I strike two tongues 11 and 12 from the section 10, the tongues being longitudinally disposed and commencing at points near the ends of the section, the tongues extending toward each other. One of the tongues is quite short, while the other is considerably longer, and both terminate with sharp points, as indicated at 11a. Thus, with the device made of spring material, the tongue 11 is designed to overlap the tongue 12 from within and bear against the same, constituting the tongue 12 as a keeper for the tongue 11. However, the flexibility of the device permits the tongue 11 to be flexed slightly in order to unhook it from the keeper, in which event the tongue 11 will project in outwardly spaced relation from the keeper. The return section 10b first originates with a slight curve 10c from the bend 10a, extending inclinedly toward the section 10 partway, and terminates with an outward curve 10d.

In order to apply the device to the back of a necktie front 13, it is set in a position shown in Fig. 1, and the back wing 13a of the necktie front pierced with the tongue 11. Then, the impaled material of the necktie is spread to also become impaled on the keeper 12, locating both the latter and the tongue 11 on the inside of the impaled material or ply. A slight pressure and lateral movement imposed on the tongue 11 will nestle it inside the keeper 12, rendering the material securing element of the retainer continuous, fully inside the material, and forming a loop in co-operation with the section 10. This arrangement exercises a complete hold on the impaled material and securely attaches the retainer to the necktie front.

The device is now firmly supported by the necktie front and presents the section 10b in the manner of a spring clasp or clip, which is slid upon the necktie tail 13b and the shirt front 14 as indicated in Fig. 2 to firmly engage the same by the tension of the section 10b against the section 10. In addition, it will be noted that the keeper 12 is formed with relatively sharp edges 12a extended inwardly from its sides, these engaging the material of the necktie fric-

tionally and retarding any tendency thereof to grasp between the tongue and the keeper and so loosen the retainer from the necktie.

In the modifications of Figs. 4 and 5, I have extended the tongue 11 with a terminal outward barb 11b and slotted the keeper 12 at 12b to receive the barb of the tongue 11 when the latter seats on the inner side of the keeper. Also, I have extended the latter with an inward terminal barb 12c which enters a cavity 11c of the tongue 11 when the parts join as described. It is seen that the engagement of the barb extensions with the respective cavities positively locks the tongue from lateral deviation and reduces the chances of its accidental disengagement.

In the modification of Figs. 6 and 7, a simplified form of the modification of Figs. 4 and 5 is shown. Here, the barbed extension 11b is had for the tongue 11, but the keeper 12 is made with one relatively large opening 12d to receive the barbed extension as clearly shown.

The modifications of Figs. 8 and 9 is similar to that of Figs. 4 and 5, except that the tongue 11 is not perforated, and the sections 11 and 10b are corrugated in order to more thoroughly grip the parts clamped.

It will be seen that the novel device in any of the forms shown serves more as an attachment for the necktie than merely as an accessory therefor. While the device is simple in its one-piece construction, it has two distinct zones of function, one being to securely attach it to the necktie front, and the other being to clamp the necktie front to the necktie tail and shirt front. Further, despite the two features involved in the device, it is fully invisible. Further, it is positioned at a point just off the center in the back of the necktie front, which is the logical position for the application of a retainer to hold

the necktie in the straight or vertical position as distinguished from the slant assumed by the same when it is clamped to one edge by the conventional necktie clasp. Further, the tongue and keeper therefor meeting and overlapping from opposite directions form a loop for the attached portion of the necktie, and leave nothing exposed in contradistinction to the locking portion of a safety pin. Finally, the novel retainer is easy to handle, apply or remove, and may be produced at low cost.

I claim:—

1. A necktie retainer comprising a section attachable to the rear of a necktie front, and a section serving as a clamp, the first-mentioned section including pointed elements extending from opposite directions and meeting in overlapping order.

2. The structure of claim 1, said elements being struck out of the material of the first-mentioned section.

3. The structure of claim 1, said elements being struck from the ends of said first-mentioned section and bent upon the latter.

4. The structure of claim 1, said elements being formed from the first-mentioned section, one element being relatively short and acting as a keeper, and the other element being long and tensioned to bear against the inner side of the keeper.

5. The structure of claim 1, said elements being formed from the first-mentioned section, one element being relatively short and acting as a keeper, the other element being long and tensioned to bear against the inner side of the keeper, and sharp edges extended inwardly from the sides of the keeper.

WALTER L. WEINSCHREIDER.
